SANDING MACHINE

Albert G. McCaleb, Evanston, Ill., assignor to
 Duro Metal Products Company, Chicago, Ill.,
 a corporation of Illinois

Application October 18, 1935, Serial No. 45,563

3 Claims. (Cl. 51—170)

My invention relates to sanding machines and is particularly concerned with improvements in sanding machines of the type characterized by an abrading element in the form of a power driven belt. The principal object of the invention is to provide a sanding machine of the aforementioned type in which the belt runs on a roller that has adequate bearings at both ends, although no part of the machine lies laterally outside of one of the edges of the belt to contact with a surface at right angles to the surface upon which the lower run of the belt is operating.

No sanding machine of the prior art, to my knowledge, presents all of the foregoing features in combination, although all are desiderata. Patent to Emmons No. 1,821,624, for example, discloses a sander which exhibits all of the aforementioned desiderata, except the provision of bearings at both ends of the belt rollers. Patent to Gustafson et al. No. 949,181, discloses a machine which also exhibits some of said desiderata. Both Emmons and Gustafson et al., however, found it necessary to employ rollers, each supported only at one of its ends, in order to keep any part of the machine from projecting laterally beyond that edge of the belt which is intended to lie and move immediately adjacent to a surface normal to the one on which the belt is operating.

The present invention, in one of its aspects, may be said to consist in the provision of a sanding machine comprising a roller driven belt, on the lower run of which the weight of the machine is carried, in which all parts of the machine frame and the bearings for the rollers lie wholly to one side of one of the edges of the belt notwithstanding that each roller is provided with adequate bearings at both ends thereof, in contradistinction to those sanding machines of the prior art wherein the problem of locating all parts of the machine frame and bearings on one side of one of the edges of the belt has been partially compromised, by the dubious and undesirable expedient of depriving each roller of support at one of its ends.

A salient feature of the present invention is the provision of means, preferably in the form of arcuate shoes, which lie closely adjacent to corresponding ends of the respective rollers and afford adequate support for that edge of the belt beyond which no other part of the sanding machine should project.

While I have chosen to illustrate the improvements of the present invention as incorporated in a sanding machine of the type that is driven

from a separate motor through the agency of a flexible shaft, I wish to have it understood that the improvements of the present invention are equally applicable to machines that are wholly self-contained in the sense that they carry their own motors. Other features, objects and advantages of the invention are apparent from the following detailed description, wherein reference is made to the accompanying two sheets of drawings, showing a preferred form of sanding machine.

Fig. 1 of the drawings is a perspective view of the sanding machine showing a driving motor and flexible shaft connected therewith;

Fig. 2 is a side elevational view thereof;

Fig. 3 is a horizontal sectional view, taken on the line 3—3 of Fig. 2;

Fig. 4 is a vertical sectional view, on an enlarged scale, taken on the line 4—4 of Fig. 2;

Fig. 5 is a vertical sectional view on a similar scale, taken on the line 5—5 of Fig. 2;

Fig. 6 is a fragmentary horizontal sectional view, taken on the line 6—6 of Fig. 2, and

Fig. 7 is an elevational view of the bearing bracket for the adjustable roller.

These specific drawings and the specific description that follows merely disclose an illustrative embodiment of the invention and are not to impose limitations upon the claims.

All the metal parts of the sanding machine, with the exception of the bolts, screws, shafts and bearings, are preferably cast from an aluminum alloy so that the device may be cheaply constructed, and of light weight. The frame 11 of the machine may be open at the front and the bottom and at one side, with a closed top 12 and side 13. At the rear of the frame or housing 11 may be provided an enlarged portion having a flat top 14 and closed rear end 15 to which are attached the legs 16 and 17 of the handle 18 of the machine. The rear end of the frame is conveniently concaved to accommodate the operator's hand as it grasps the handle, and a second handle 19 shaped like a door knob may be screwed to the top member 12 of the frame for the other hand of the operator.

Means may be provided at the front of the side member 13 of the frame for supporting one end of a roller. Thus, the side member 13 may have a boss 20 with a bore in which is fixed a bearing 21 of any suitable bearing metal. In this bearing is journaled the end 22 of a shaft having a knurled portion 23 to receive a roller 24 with a drive fit. The frame also carries means for rotatably mounting the other end of the roller, having a

support for the part of a sanding belt running on the roller that extends past the end of the roller. In the device illustrated, the shaft upon which the roller is mounted has its other end 25 journaled in a bearing 26 fixed in a bore in an arcuate shoe 27, which is formed at the end of a web 28 integral with the side member 13. A shoe is preferable to a roller for supporting the overlapping part of the belt, because a shoe can be made to extend close to the outer edge of the main roller, while a roller used in place of a shoe would have to be spaced from the main roller to provide room for a support between the two rollers to carry their bearings.

15 The other roller of the machine is preferably supported by a bracket that is adjustable relatively to the frame. For mounting the adjustable bracket, there may be inserted in a pair of bores, in the shoulder 29 at the front of the enlarged 20 rear portion of the frame, two bolts 30 that have headless ends fixed by means of set screws 31 in bores in the upper arm 32 of the adjustable bracket. In order that the bracket may be freely 25 adjustable, the bores in the shoulder 29 are made slightly larger than the bolts, and a tapped hole is provided between the bores to receive a screw bolt 33 whose end bears against the upper arm 32 of the adjustable bracket. To adjust the tension of a belt running on the two rollers by moving the 30 bracket forward or backward the nuts on the bolts 30 are screwed up, or the screw bolt 33 is screwed in. The bracket can also be tilted slightly to cause the axis of its supported roller to tilt in a horizontal plane, by screwing up the nut on 35 one bolt more than on the other. In this manner the belt can be made to run to one side or the other.

Depending from the upper arm 32 of the adjustable bracket may be a leg 34 at the end of 40 which is formed a boss 35 having a bore containing a bearing 36 of any suitable bearing metal. This bearing receives the end 37 of a shaft having a knurled portion 38 for the securing of a roller 39 similar to the roller 24. The roller 39 is preferably provided with a support for its other end 45 that is similar to the support for the corresponding end of the roller 24, except that it is integral with the adjustable bracket rather than with the frame. To support this end of the roller the shaft may have its end 40 journaled in a bearing 41 fixed in a bore in an arcuate shoe 42 formed on the end of an arm 43 that extends around the roller from the depending leg 34 of the bracket. The roller may be driven by a flexible shaft 44 50 threaded into the end 37 of the roller shaft, the threads running in the direction in which the shaft is to be rotated. The flexible shaft 44 is provided with a cover 45 and is driven by a motor 46.

60 Also included in the device may be a means for supporting the frame upon the lower run of the belt that passes over the rollers, such as a shoe 47 extending nearly the whole distance between the rollers. Supporting the sanding machine upon the shoe is conveniently carried out by provision of a hollow boss 48 on the top of the shoe, into which is driven a heavy pin 49 that is fixed by means of a set screw 50 in an ear 51 extending inward from the side member 13. To 65 retard conduction of heat generated by the friction of the belt against the work, the shoe 47 is

covered with one or more layers 52 of heat-insulating material, such as cork. These layers may in turn be covered with a friction reducing apron 53 of sheet steel having a flange 54, which is screwed to the shoe to hold the apron 53 in place, and which is separated from the apron by means of a flexible crease that permits the apron to adjust itself to the work. Around the shoe and the rollers is wrapped a belt 55 of flexible abrasive material such as emery cloth or sand 10 paper. The shoe is adjusted to cause the belt to project downward to a slight extent between the rollers so that a flat work engaging surface is presented. In order that all parts of the machine may lie wholly inside the plane of the edge of the 15 belt, the shoe and rollers should extend no farther outward than the belt edge. The frame preferably does not even extend as far out as the belt (see Figure 4). The rollers 24 and 39 may have a slight crown opposite the middle of the 20 belt to keep the belt from running off to one side and may be covered with resilient rubber tubes 25 that grip the roller surfaces and provide anti-slip engagement with the interior of the belt.

The sanding machine that has been described 25 may be modified, and various other devices embodying the substance of the invention may be constructed, to meet various requirements.

Having thus described my invention, I claim:

1. In a sanding machine, in combination, a 30 frame, a drive roller and an idle roller, each having one end rotatably supported by the frame, a sanding belt on the rollers extending past their other ends, means for supporting the frame upon the lower run of the belt, and an arcuate shoe 35 carried by the frame for supporting the part of the belt that overlaps each roller having means for rotatably supporting the other end of the roller and lying inside the plane of the edge of the 40 belt.

2. In a sanding machine, in combination, a 45 frame, a drive roller and an idle roller, each having one end rotatably supported by the frame, a sanding belt on the rollers extending past their other ends, means for supporting the frame upon the lower run of the belt, and an arcuate shoe carried by the frame for supporting the part of the belt that overlaps each roller having means for rotatably supporting the other end of the 50 roller and lying inside the plane of the edge of the belt, the arcuate shoe carrying the drive roller being adjustably mounted on the frame for tensioning the sanding belt on the rollers.

3. In a sanding machine, in combination, a 55 frame, a drive roller and an idle roller, each of said rollers having both of its ends supported by the frame, an endless sanding belt on the rollers, said belt overlapping corresponding ends of the rollers and extending to a plane, at right angles to the roller axes, beyond which no frame part 60 extends, and auxiliary belt-supporting members at those ends of the rollers which are overlapped by the belt, each said auxiliary belt-supporting member being carried by a frame part which lies between those portions of the belt which extend 65 between the rollers, and each said auxiliary belt-supporting member presenting a curved surface, concentric with the adjacent roller, for engaging and supporting the belt edge which overlaps the contiguous end of the adjacent roller. 70

ALBERT G. McCALEB.
